UNITED STATES PATENT OFFICE.

WILLIAM C. CARPENTER, OF LOS ANGELES, CALIFORNIA.

DRiER.

Application filed December 3, 1925. Serial No. 72,899.

My invention relates to improvements in driers of the particular type that are designed for the rapid and economical drying of sawdust, shavings, and like comminuted 5 vegetable matter or in fact any pulverized or granular products that require partial or complete drying before being put to its particular use.

The principal objects of my invention are 10 to provide a drier that is relatively simple in construction and which may be economically operated for thoroughly drying large quantities of pulverized or comminuted material, to provide improved means for delivering the material to be dried into one 15 end of the drier and effecting the discharge of a material from the other end of said drier, to provide an improved arrangement whereby heated air, gases, or the like are 20 caused to travel first in one direction through the entire length of the drier chamber or drum, and thence in the opposite direction for the entire length of the drier, and further to generally improve upon and simplify 25 the construction of the existing forms of rotary driers and particularly those used for drying wood shavings, sawdust, peat, straw, and other matter that is used in the manufacture of fuel briquets.

With the foregoing and other objects in view, my invention consists in certain novel 30 features of construction and arrangement of parts that will hereinafter be more fully described and claimed and illustrated in the accompanying drawing, in which—

Fig. 1 is a vertical section taken lengthwise through the center of a drier of my improved construction.

Fig. 2 is an enlarged section taken on the 40 line 2—2 of Fig. 1.

Fig. 3 is an enlarged cross section taken on the line 3—3 of Fig. 1.

Fig. 4 is an enlarged cross section taken on the line 4—4 of Fig. 1.

Referring by numerals to the accompanying drawing which illustrates a practical embodiment of my invention, 10 designates a drum or hollow cylinder preferably formed of suitable sheet metal and of any desired 50 diameter and length. For all practical purposes this drum may be from 4 to 8 or 10 feet in diameter and from 30 to 60 feet in length. The inlet end of this drum is closed by a head 11 and the opposite or outlet end 55 of the drum is provided with a conical shell 12 and the latter being provided at its outer

end with a circular discharge opening 13. Carried by the end of the shell 12 and disposed around opening 13 is a ring 14 that is channel shape in cross section and which receives the inturn flange 15 that is formed on the upper portion of a dried material chute 16.

The inlet end of the drum 10 is positioned within the cylindrical portion of a hot air furnace 17 and the drum, when set up for use, occupies a slightly inclined position relative to a horizontal plane so that its discharge end is slightly lower than its inlet end.

Secured on the outer face of the drum and at points suitably spaced apart are circumferential rails 18 that bear on grooved rollers 19, the latter being mounted in suitable bearings.

Secured on the drum, preferably at an intermediate point, is a circular rack 20 with which engages a gear wheel 21, the latter being carried by a driving shaft 22, and which latter, when rotated, imparts rotary motion to the drum through said gear wheel 21 and rack 20.

Formed in the center of head 11 is a circular aperture 23 through which passes the lower end of an inclined tube 24, the same 85 extending outwardly and upwardly at an angle through the top of the furnace extension 17.

Extending lengthwise through this inclined tube is a centrally arranged partition 25 that divides the space within said tube into an upper air outlet duct 26 and a lower material inlet duct or chute 27. The upper end of the material inlet chute communicates with a hopper 28 that is located externally of the furnace member 17 and the upper end of air outlet duct 26 communicates directly with a stack 29.

Air leakage through the joint between tube 24 and opening 23 is minimized by a suitable packing arrangement between head 11 and tube 24 and which arrangement preferably comprises overlapping ring flanges 24^a that are secured to said tube 24 and head 11.

The partition 25 is arranged so that its lower or inner end occupies a position above the axis of the tube 24 while its upper end occupies a position below the axis of said tube 24 and thus the material inlet chute 27 gradually increases in cross sectional dimensions toward its lower end with the result

that the material will readily pass through said chute without clogging.

Hinged to the lower end of the partition 25 is the upper straight edge of a semi-circular plate 30, the same being free to swing in both directions. While the drier is in operation and material is passing through chute 27, plate 30 will swing outward and upward as a result of the pressure of the material against its inner face and its lower edge will drag over the material that is discharging into the drum 10. As a result of this arrangement, the air that is discharging from the drum will pass through open outlet 26 rather than through the practically closed material inlet duct 27.

Secured to the inner face of conical member 12 are material discharge chutes 31, preferably constructed of suitable sheet metal that are bent into spiral shape when viewed in elevation or cross section, and which chutes are designed to pick up the dried material while at the bottom or lower portion of their circular path of travel and to permit the discharge by gravity of said material as said chutes pass through the upper portion of their circular travel and during which latter period said chutes occupy the inclined position as shown by the upper one of said chutes in Fig. 1.

Arranged within the drum 10 immediately adjacent to the wall thereof and extending the entire length of said drum are tubular members 32 that are preferably formed of suitable sheet metal and the forward or inlet ends of said tubes are seated in head 11.

The ends of the tubes 32 that terminate adjacent to conical member 12 are reduced in diameter and said reduced ends are rebent as designated by 33 and said re-bent ends project a short distance lengthwise toward the inlet end of the drier so as to form short jet nozzles 34.

These tubes are for the purpose of conducting heated air and gases lengthwise through the body of the drier at a point adjacent to the wall of drum 10 and said heated air and gases discharge from the jet nozzles 34 and pass in the opposite direction or rearwardly through the central portion of the drum and through outlet duct 26 to stack 29.

Tubes 32 are retained in position adjacent to the wall of drum 10 by ring-shaped frames 35, the latter being secured to the wall of drum 10 by bolts such as 38 and secured to each ring-frame 35 are the outer ends of radially disposed arms 39, the inner ends thereof occupying recesses that are formed in a centrally arranged ring-shaped bearing block 40.

Passing radially through each ring-shaped bearing block is a series of set screws such as 41 the outer ends thereof bearing directly against the inner ends of the corresponding

arms 39. When the set screws 41 are tightened against the inner ends of the arms 39 the corresponding ring-shaped frame 37 will be forced outward with considerable pressure thereby clamping the tubes 32 against saddle blocks 42 and which latter are disposed between each tube 32 and the wall of drum 10 (see Fig. 3).

Arranged between the tubes 32 and extending between the shell of drum 10 and the rings 37 are radially disposed plates 43 that extend the entire length of the drum and the inner edges of these plates are bent laterally to form lips or flanges 44. These plates with their flanged inner edges function as carriers to pick up the pulverized material from the bottom of the drum and carry the same upward to the top of the drum from which latter point the material will discharge from said carriers and pass backwardly to the bottom portion of the drum.

The operation of my improved drier is as follows:

The drum is rotated by the operation of power driven shaft 22 and the sawdust, shavings, or other material to be dried is delivered to the inlet end of the drum through chute 27. A blower forces heated air and gases from the furnace into and through tubes 32 thereby providing a heating zone entirely around the wall of the drum and the heated air and gases, after passing through the tubes 32, discharge from nozzles 34 and pass lengthwise through the central zone of the drum and said air and gases, which are practically cooled by the time they enter the upper portion of tube 24, pass off through outlet duct 26 and stack 29.

As drum 10 continues to rotate the material to be dried will pass over the heated tubes 32 and the material that is caught between said tubes and by the carriers 43 will be carried upward to the top of the drum, from which point said material will drop back to the lower portion of the drum and in so doing said material will encounter the heated air that is passing through the central portion of the drum.

Obviously the material that is being dried will absorb a considerable portion of the heat from the highly heated air and gases passing through tubes 32 so that the temperature of the air and gases discharging from the nozzles 34 will be lowered to such a degree as to preclude any possibility of ignition of the material that is passing through the drum.

As the drum continues to rotate the material will gradually pass to the discharge end of said drum owing to the inclined position of the drum and as the spirally bent chutes 31 pass through the lower portion of their circular path of travel they will pick up the dried material and carry the same to the

top of the path of travel and from which latter point said dried material will, by the inclination of the spirally bent chutes, discharge downwardly therethrough and pass into outlet chute 16.

Thus it will be seen that I have provided a drier that is relatively simple in construction, capable of being easily and cheaply produced and which is very effective in performing its intended functions. An especially desirable feature of my improved drier is the arrangement of the heated air and gas conveying tubes around the wall of the drum and the re-bent ends of said tubes whereby the heated air and gases are caused to travel first in one direction and then in the opposite direction entirely through the drum, thus materially increasing the efficiency and capacity of the drier.

It will be understood that minor changes in the size, form and construction of the various parts of my improved drier may be made and substituted for those herein shown and described without departing from the spirit of my invention, the scope of which is set forth in the appended claims.

I claim as my invention:

1. In a drier, a rotary drum having a material inlet at one end and a material outlet at the other end, a series of heated air ducts arranged on the interior of the drum and extending lengthwise adjacent to the wall thereof, and the discharge ends of which air ducts terminate within the drum adjacent to one end thereof and said discharge ends being re-bent so as to discharge heated air lengthwise through the chamber in the drum between said series of air ducts.

2. In a drier, a rotary drum having a material inlet at one end and a material outlet at the other end, a series of heated air ducts arranged on the interior of the drum and extending lengthwise adjacent to the wall thereof and the discharge ends of which tubes are re-bent and projected toward the end of the drum that is provided with the material inlet.

3. In a drier, a rotary drum, a series of heating tubes extending lengthwise therein and arranged adjacent to the wall of the drum, the discharge ends of which heating tubes are re-bent within the drum to form nozzles that discharge heated air lengthwise through the chamber in the drum between

said series of heating tubes, one end of said drum being provided with a material inlet and an air outlet and the opposite end of said drum being provided with a dried material outlet.

4. In a drier, a rotary drum, a series of heating tubes extending lengthwise therein and arranged adjacent to the wall of the drum, one end of said drum being provided with a material inlet and an air outlet, the opposite end of said drum being provided with a dried material outlet and a plurality of dried material discharge chutes occupying inclined positions within the drum adjacent to the material outlet therefrom.

5. In a drier, a rotary drum, one end of which is tapered and provided with a dried material outlet opening and a series of material discharge chutes arranged on the inner face of the tapered end portion of said drum.

6. In a drier, a rotary drum, one end of which is tapered and provided with a dried material outlet opening and a series of material discharge chutes arranged on the inner face of the tapered end portion of said drum, each of which discharge chutes comprises a section of sheet metal bent into spiral form.

7. In a drier, a rotary drum, a series of heating tubes extending lengthwise on the interior of said drum adjacent to the wall thereof, the ends of which tubes at one end of the drum are open and communicate with the exterior of the drum and the opposite ends of which tubes are re-bent so as to form short longitudinally disposed discharge nozzles.

8. In a drier, a rotary drum, a series of heating tubes extending lengthwise on the interior of said drum adjacent to the wall thereof, the ends of which tubes at one end of the drum are open and communicate with the exterior of the drum, the opposite ends of which tubes being re-bent so as to form short longitudinally disposed discharge nozzles, a material inlet chute leading into one end of said drum and an air outlet chute arranged adjacent to said material inlet chute.

In testimony whereof I affix my signature.

WILLIAM C. CARPENTER.
